MICROSCOPE ILLUMINATOR OR SIMILAR ARTICLE

Willard H. Korte, North Miami Beach, Fla., assignor to
Tasco Sales, Inc., Miami, Fla., a corporation of Florida

Filed Oct. 1, 1965, Ser. No. 87,269

Term of patent 14 years

(Cl. D57—1)

FIG. 1 is a front elevation of a microscope illuminator or similar article, showing my new design.

FIG. 2 is a side elevation thereof, with the electric cord broken away for convenience of illustration.

FIGURE 3 is a rear view thereof.

FIGURE 4 is a top plan view thereof.

FIGURE 5 is a side elevation thereof, the broken line showing of the microscope is for illustrative purposes only.

This application is a continuation-in-part of my co-pending application Serial No. D. 86,807 filed September 2, 1965 and now abandoned.

The side opposite to the side shown in FIG. 2 is of similar appearance.

I claim:

The ornamental design for a microscope illuminator or similar article, as shown and described.
